UNITED STATES PATENT OFFICE

ROBERT A. MOORE, OF NEW YORK, N. Y., ASSIGNOR TO MULTIPLE SELLING CORPORATION, OF NEW YORK, N. Y.

SAFETY LAMP LOCK

Application filed January 29, 1929. Serial No. 335,786.

This invention relates to locking devices and more particularly to lamp locks.

One object of the invention is to provide an improved locking device for interengaging male and female screw members, which locking device is mounted upon the male member.

Another object of the invention is the provision of a device of the character described wherein a locking member adapted to engage between the circular walls of the interengaging members is mounted in an improved manner upon the male member and is movable in the direction of the axis of the said male member.

Another object of the invention is to construct a device of the type mentioned having a locking member movably mounted on the male member of a pair of interengaging male and female screw members, there being an actuator having detachable engagement with the locking member to withdraw the same from locking engagement, and having improved coaction with the mounting for the locking member to facilitate the operation of the device.

A further object of the invention is the provision of an improved device of the type mentioned which comprises few and simple parts, is inexpensive to manufacture, easy to assemble, convenient to apply and use, rugged and compact in construction, and reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

45 In the drawing:

Figure 1 is a perspective view of a device embodying the invention.

Fig. 2 is a sectional view showing an application of the invention in locking position of 50 same.

Fig. 3 is a view of the invention applied to the male member.

Fig. 4 is a view showing the application of the actuator for unlocking the device.

Fig. 5 is a side view of the complete actuator tool.

Fig. 6 is an edge view of the same with parts removed.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, the invention provides a locking device which is applicable to male and female interengaging screw members to prevent unauthorized disengagement of the same. This invention finds a particular use in connection with sockets and lamp bases or plugs. The device includes a locking member which has been more particularly described in my patent issued in the United States on April 23rd, 1929, No. 1,710,373. This locking member has its opposite side edges lying along an angle with the tangent to the male member, in this case, the lamp base.

These opposite edges are adapted to cut into the circular walls of the interengaging members to prevent unscrewing of the same. Movably supporting the locking member is a resilient arm which is carried by a ring disposed about the male member. This ring is preferably placed on the male member before the same is threaded into the female member and is disposed so as to accurately carry the locking member into the space between the said circular walls, without requiring handling or manipulation on the part of the operator. The said ring is preferably of angular construction in cross section and includes a flange coaxial with the male member and another flange extending at right angles thereto,

The said arm is positioned within the coaxial flange referred to and has one of its ends rigidly secured thereto. Being made of comparatively thin metal, both the arm and its supporting flange are insertable into the socket between the male member and the sleeve of insulation. The carrying flange has a cut-out to receive the locking member. Extending from the said arm through the said 10 cut-out is a retractor portion which is adapted to be detachably engaged by an actuator, the latter having bearing relation with the laterally extending flange to permit a pull or tension to be exerted on the arm to deflect the 15 same and withdraw the locking member from between the walls of the male and female interengaging members. Where the invention is applied in connection with a lamp base having a projection of solder to secure the 20 leading-in wire of a filament, the carrying flange may have an opening to receive this projection.

Referring in detail to the drawing, 10 denotes a device embodying the invention. The 25 same includes a ring 11 which is preferably of one-piece construction and can be made of any suitable material possessing sufficient strength and stiffness to adequately support the locking member. The ring 11 is preferably of closed form although it will be appreciated that it can also be open. The ring may be stamped of thin sheet metal so as to be of angular cross section, including a vertical flange 12 extending coaxially with the male member, and a laterally extending flange 13 lying at right angles thereto. Disposed within the annular flange 12 is an arcuate arm 14 which extends therelong. The said arm is secured to the flange 12 in any suitable manner as, for example, by spot welding at 15. From 30 that point, the arm extends through an angle of approximately 180° in increasingly spaced relation to the flange 12, but nevertheless in relative proximity thereto throughout its length. While the upper edge 16 of the arm lies approximately in the plane of the upper edge of the flange 12, the lower edge 17 of the said arm lies spaced inward from the bottom edge of the flange 12 represented by the bend 35 18. At its free end the arm 14 has a locking member 19 that extends upward from the said arm in the general direction of the axis of the male member into the space between the circular walls of the interengaging male and female members. Since the opposite edges 20 and 21 of the locking member lie along an angle with the tangent to the male member, these edges will tend to bite into the said circular walls as hereinafter more particularly described. A cut-out 22 in the flange 12 is adapted to receive the locking member and to 40 provide ample clearance therefor. Extending downward from the arm 14 is a retractor 23 having a head 24. This retractor lies within 45 the cut-out mentioned.

The manner of applying the device 10 will now be clearly apparent. 25 represents one type of unit comprising interengaging male and female screw members which take the form of a socket 26 and a lamp base 27. The 50 socket is of conventional construction including a casing 25a, a sleeve of insulation 28 therein, and a contact shell 29 within the sleeve. The contact shell terminates at 30 within the opening of the socket and in spaced relation to the ends of the casing and insulating sleeve. The lamp base is of conventional construction and includes a metal male contact shell 31 having near its line of junction with the bulb a projection or tip of solder 32 that serves to form a connection between the shell 31 and a leading-in wire of the filaments. The device 10 is applied over the male member or lamp base 27 approximately to the line of junction 33 of the lamp base with the glass body of the lamp. The 55 bend at 18 forms an entrance facilitating the positioning of the ring on the lamp base, particularly in view of the fact that the edge 17 of the arm is in spaced relation to the said bend. The flange 12 acts as a collar and receives the lamp base with a slight degree of clearance and the said flange accommodates the projection of solder 32 by means of an opening 34 that receives the same. This projection of solder accordingly acts as a means for aiding in holding the ring 11 comparatively rigidly on the lamp base. The locking member 19 extends alongside the lamp base and in the direction of the axis thereof. 60 The retractor 23 passes downward through the cut-out 22 to allow for the bulge at 35 in the glass body 36 of the lamp. The retractor may be bent outward slightly at 37 so that the head 24 lies in close proximity to the 65 said glass body. With the device 10 positioned on the lamp base, the latter is screwed into the socket 26, causing the locking member 19 to enter between the circular walls of the interengaging members, and more particularly, between the lamp base and the contact shell 29. Coincidentally, the flange 12 enters the socket to lie disposed within the sleeve of insulation and along the end of the 70 said contact shell. The arm 14 will at this 75 time be comparatively stationary between the flange 12 and the lamp base, where it may be retained with a slight clearance. The flange 13 lies in proximity to the end of the socket and its diameter is approximately 80 equal to that of the casing 25a of the socket. 85

On attempting to unscrew the male member or lamp base from the socket, the opposite edges 20 and 21 of the locking member 19 bite into the circular walls and so prevent 90 unscrewing. The head 24 of the retractor can, however, be engaged by a suitable tool 37 to exert a pull on the arm 14 in an axial direction and thus withdraw the locking member from between the lamp base and 95

socket. When thus withdrawn, the tension on the head 24 may be continued during the unscrewing operation, or the tool 37 removed since the locking member 19 may then abut the end of the contact shell 29, and after a slight turn of the lamp base is executed, the locking member will not be able to engage between the lamp base and the wall of the socket. Thus the lamp base may be conveniently unscrewed from the socket.

The actuator or tool 37 may be of any convenient type, and for the sake of illustration may be shown as including a metal shank 38 having a handle 39 of insulating material, or the like. The shank 38 has an offset portion 40 at its free end which offset portion is formed with a pair of spaced lugs 41 that are reversely bent to form hooks. Extending laterally from the portion 40 is an arm 42 which may be secured thereto in any suitable manner. The end 43 of this arm acts as a pivot point and is disposed beyond the lugs 41 to contact the underside of the flange 13 when the lugs 41 are engaged over the head 24. As thus positioned, the tool 37 has bearing engagement with the ring 13 so that on moving the tool laterally as shown by arrow *a* in Fig. 4, a pull is exerted on the retractor in a direction generally parallel to the axis of the lamp base to withdraw the locking member from holding position. The device shown in Fig. 4 thus represents all of the features entering into the invention and illustrates the simple coaction of the parts and the ease with which they may be manipulated.

It will be appreciated that within the scope of the invention various modifications may be made, as, for example, with relation to the character of the ring 11 in which the flanges 12 and 13 may be altered or reduced, and made if desired for screw co-operation with the male member or lamp base. Further it is noted that the locking member 19 need not enter at all between the threads of the interengaging screw members, but that it will suffice that it enter between the circular walls of the said members.

I claim:

1. A lamp locking device, including, in combination, male and female interengaging screw members, a support mounted on the male member, a locking member extending between the circular walls of the interengaging members, said locking member having edges lying along an angle with the tangent to the male member to bite into the said circular walls on attempting to unscrew the male member, means on the support movably carrying the locking member for withdrawal from between the said circular walls, and other means to withdraw the locking member to permit the male member to be unscrewed.

2. A lamp locking device, including, in combination, male and female interengaging

screw members, a lock between the screw walls of said interengaging members to prevent unscrewing of the same, and means on the male member carrying the lock for movement in a direction parallel to the axis of the male member for withdrawal of the lock from between the screw walls to permit unscrewing of the members.

3. A lamp locking device, including, a socket, a male member having screw engagement in the socket and making electrical contact therewith, said socket having a casing, a sleeve of insulation therein, and a contact shell in the sleeve of insulation, the contact shell terminating in spaced relation to the end of the casing, a ring mounted on the male member, said ring lying within the casing between the end thereof and the end of the contact shell, a locking member having opposite edges disposed along an angle with the tangent to the male member, said locking member extending between the contact shell and the screw wall of the male member to prevent unscrewing of the latter, and means movably mounting the locking member on the ring to permit withdrawal of the locking member from between the contact shell and the screw wall of the male member.

4. A lamp locking device as set forth in claim 3, wherein said ring includes a laterally extending shoulder portion outside of the socket, and actuator means to detachably engage the locking member, said actuator means having bearing engagement with the shoulder to permit the same to exert a pull on the locking member for withdrawal of the same.

5. A lamp locking device, including male and female interengaging screw members, a locking member having opposite edges disposed along an angle with the tangent to the male member, said locking member extending between the circular walls of the interengaging members to prevent unscrewing of the same, a ring on the male member outside of the female member, means mounting the locking member on the ring for movement in the direction of the axis of the male member for withdrawal of the locking member from between the said circular walls, said ring comprising a laterally extending shoulder portion, and an actuator having detachable engagement with the locking member and bearing engagement with the said shoulder portion to exert a pull on the locking member for withdrawal thereof as aforesaid.

6. A lamp locking device, including, in combination, male and female interengaging screw members, a ring mounted on the male member, said ring being of angle cross section to include annular flanges one of which is coaxial with the male member, and the other of which extends at an angle to the axis thereof, a locking member extending

between the circular walls of the screw members and having its opposite edges lying along an angle with the tangent to the male member to bite into the said walls on attempting to unscrew the male members, an arcuate arm connected to the said coaxial flange and extending therealong, said locking member being mounted on the end of said arm to remove the locking member from locking engagement, said means including a detachable actuator having bearing engagement with the angularly extending flange to exert a pull in an axial direction on said arm.

15 7. A lamp locking device as set forth in claim 6, wherein the said coaxial flange has a cut-out to receive the locking member.

20 8. A lamp locking device as set forth in claim 6, wherein said male and female interengaging screw members consist of a lamp base, and a socket, the lamp base having a projection of solder for a terminal of the filament connection, the said coaxial flange having an opening to receive said projection.

25 9. A lamp locking device as set forth in claim 5, wherein said locking member includes a coacting headed retractor portion, and said actuator has a pair of spaced lugs to take over the head of the retractor, and a lever arm pivotally bearing on the shoulder portion.

30 10. A lamp locking device, including a lamp base, a socket therefor, said lamp base having a projection of solder for a terminal of the filament connection, a supporting element mounted on the lamp base and in engagement with said projection, and a locking member carried by the supporting element, said locking member being engageable with the socket coincident with the engagement of the lamp base in the socket to prevent removal of the lamp base from the socket.

35 11. A device including, in combination, male and female interengaging screw members, a circular member engaging removably around the male member and carried thereby, and a locking member carried by the circular member to prevent unscrewing of the male and female members, said locking member being positioned adjacent to the thread of said male member and extending in a generally axial direction, said locking member being inserted between the threads of the male and female members and having a small cross section to be so insertable coincident with the interengagement of the male and female members, in which position of the same the circular member lies uniformly at the opening of the female member, said locking member being of a length to enter substantially only to the extent of a thread into the female member.

In testimony whereof I affix my signature.
